(57) **CLAIM**

The ornamental design for a multiple purpose light, as shown and described.

DESCRIPTION

FIG. 1 is a perspective view of the multiple purpose light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a circle portion 9 of FIG. 8, shown separately for completeness of illustration.

The broken lines are for the purposes of illustrating portions of the multiple purpose light and form no part of the claimed design.
